SUBSURFACE APPARATUS FOR OPERATING
WELL EQUIPMENTReuben C. Baker, Coalinga, Calif., assignor to
Baker Oil Tools, Inc., Vernon, Calif., a corpora-
tion of California

Application April 17, 1950, Serial No. 156,481

18 Claims. (Cl. 166—63)

1

The present invention relates to well devices, and more particularly to apparatus for performing subsurface operations or functions in oil, gas and similar wells.

An object of the invention is to provide well apparatus embodying its own source of fluid pressure for operating the apparatus, in which the fluid pressure can be supplied by a relatively safe compressed medium, preferably of non-combustible or non-explosive characteristics, which can be released in a comparatively gradual manner to provide a gradual increase in pressure of the fluid acting on the apparatus.

Another object of the invention is to provide an improved manner of releasing a compressed gaseous medium in apparatus of the character above indicated.

A further object of the invention is to provide pressure operated subsurface well apparatus, in which the source of pressure is confined in a container that can be installed readily within the apparatus and easily removed from the latter after its use.

Yet another object of the invention is to provide pressure operated subsurface well apparatus, in which the source of gas pressure is confined in a container that can be easily placed within and removed from the apparatus, the gas being releasable from the top of the container and capable of operating upon the portion of the apparatus below the container.

Still a further object of the invention is to provide pressure operated subsurface well apparatus, in which a gas under pressure is confined in a container and is released, when desired, by devices that preclude inadvertent subsequent closing of the container.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a side elevation, partly in section, of the apparatus, with the parts in position for lowering through a well casing, or similar well conduit.

Figs. 2a and 2b together constitute a longitudi-

nal section, on an enlarged scale, of the apparatus disclosed in Fig. 1, Fig. 2b being a lower continuation of Fig. 2a;

Figs. 3a and 3b are views similar to Figs. 2a and 2b, illustrating the apparatus after the gas pressure therein has been released, in order to set a portion of the apparatus in the well casing;

Fig. 4 is a partial section, on an enlarged scale, of the valve and valve releasing portion of the apparatus;

Fig. 5 is a cross-section taken along the line 5—5 on Fig. 3b.

Fig. 6 is a longitudinal section through the compressed gas releasing valve portion of the apparatus, with the safety and filling cap assembled therewith.

The apparatus is disclosed in the drawings as including a setting tool A connected to a well packer or bridge plug B that is to be anchored at a desired point within a string of well casing, or similar well conduit C. The apparatus may be lowered through the well casing by means of a running-in string D, which may be a wire line secured to the upper end of the setting tool A and extending to the top of the well bore.

The well packer B, which forms the lower portion of the apparatus, may assume any of several desired forms. As illustrated, it concludes a tubular main body 10 whose central passage 11 may be closed by a plug 12. A guide 13 is secured to the lower end of the body to prevent inadvertent hanging up or stopping of the equipment in casing joints or coupling spaces during its lowering through the well casing C.

The packer can be anchored against downward movement in the well casing by a plurality of lower segmental slips 14 having their lower ends engageable with the guide 13, as well as with a lower abutment or flange 15 on the body. The inner surfaces 16 of these slips are tapered in a downward and inward direction for slidable engagement with a corresponding externally tapered surface 17 on a flusto-conical expander 18 slideable on the body 10. This lower expander is connected to the lower end of a packing sleeve 19, of rubber or similar material, disposed around the body 10. The upper end of the packing sleeve is, in turn, connected to an upper expander 20 having an upward and inwardly inclined externally tapered surface 21 engageable with corresponding tapered surfaces 22 on a plurality of upper segmental slips 23, which are adapted to be embedded in the well casing C, to preclude upward movement of the well packer therewithin.

The slips 14, 23 and packing element 19 are

retained initially in retracted positions with respect to the packer body 10. Thus, shear screws 24, 25, or other suitable frangible connecting elements, secure the upper and lower conical expanders 20, 18 to the body, with the intervening packing sleeve 19 held in retracted position. The upper and lower slips 23, 14 are also held in retracted positions by shear screws 26, 27 attaching them to their associated upper and lower expanders 20, 18.

The shear screws 26 which attach the upper slips 23 to the upper expander 20 have a combined shearing strength which is substantially less than the shear value of the screws 24 holding the upper expander to the body 10. These latter screws have a lesser shear value than the screws 25, 27 securing the lower expander 18 to the body 10 and lower slips 14 to the lower expander. These relative shear values are selected to obtain detachment first of the upper slips 23 from the upper expander 20 and movement of the upper slips downwardly along the upper expander and radially outward into anchoring engagement with the casing wall. A subsequent upward strain and pull taken on the packer body 10 then shears the screws 24 holding the upper expander 20 to the body 10, and moves the lower expander 18 and slips 14, as a unit with the body 10, toward the upper expander 20 and slips 23, effecting foreshortening of the packing 19 and its compression between the expanders 20, 18, forcing the packing outwardly into firm sealing engagement with the wall of the casing C.

Subsequent increase in the upward pull or force on the packer body 10 substantially simultaneously shears the screws 25, 27 holding the lower expander 18 to the body 10 and the lower slips 14 to the lower expander, to cause the lower flange 15 and guide 13 on the body to shift the lower slips 14 upwardly along the lower expander 18 and radially outward into anchoring engagement with the casing wall. A split, contractile ring 38 may be disposed in the upper expander 20 for engagement with one of several circular ratchet teeth 31 formed on the exterior of the body, to lock the latter against downward movement.

It is apparent that the space between the body 10 and casing wall has been sealed off by the packing sleeve 19, that upward movement of the packer is prevented by the upper expander 20 and slips 23, and that downward movement is prevented by the lower expander 18 and slips 14. This condition is exemplified in Fig. 3b, and results from a definite sequence of steps or operations. Thus, the upper slips 23 are first moved outwardly to casing engaging position, the packing element 19 is then expanded against the casing C, and the lower slips 14 then engage with the casing. A definite time interval should preferably elapse between these main operations or steps, to insure proper setting of the well packer in the casing. In the form of invention disclosed in the drawings, the operational sequence is furnished by the use of a gaseous pressure, which is released and imposed within the setting tool A, in order to gradually build up a pressure in the latter. The provision of the motivating force within the setting tool also enables the well packer B to be run in the casing C on a wire line D.

The gas pressure is provided within the setting tool A. This tool consists of a cylinder 32 including a generally cylindrical sleeve 33 threaded onto both an upper head 34 and a lower head 35. A piston 36 is slidably mounted in the cyl-

inder, this piston carrying one or more piston rings 37 to prevent leakage between it and the cylinder. The upper end of a piston rod 38 is threaded to the piston, extending downwardly through the lower cylinder head 35 to a point therebelow, where an anvil or cross-piece 39 is mounted within a transverse slot 40 in the rod. Leakage between the rod and lower cylinder head is prevented by suitable rod packing 41 mounted in the lower head 35 and engaging the periphery of the rod 38.

The downward force or movement of the piston 36 and piston rod 38 is transferred to the upper slips 23 of the packer B. The relative upward movement of the cylinder 32 is transferred to the packer body 10. In this manner, the above-noted operational sequence of anchoring the packer in packed-off condition within the well casing is obtained. To accomplish such sequence of operations, a tubular actuating mandrel 42 is threaded to the lower end of the lower cylinder head 35. The lower end of this mandrel has a transverse frangible pin 43 extending through it, and also into a sleeve 44 that is threaded into the upper end of the body 10.

The piston rod 38 is movable downwardly within the bore 45 of the actuating mandrel 42, the cross-piece 39 projecting in opposite directions from the rod through diametrically opposed longitudinal extending slots 46 formed through the mandrel wall. The cross-piece also extends into opposed slots 47 formed through a setting ring or sleeve 48 slidably mounted on the actuating mandrel 42, and forming a connection between the piston rod 38 and ring 48. A setting sleeve or skirt 49 is adjustably threaded on the setting ring 48, this skirt depending from the ring, with its lower end engaging the tops of the upper slips 23.

40 The gaseous force operating the equipment is developed within the cylinder 32 above the piston 36. This force moves the piston 36 and piston rod 38 downwardly, and cylinder 32 relatively upwardly. The downward movement of the rod 38 is transmitted to the setting sleeve 49 through the anvil 39 and setting ring 48, while the upper movement of the cylinder 32 is transmitted to the packer body 10 through the actuating mandrel 42, frangible pin 43 and sleeve 44.

50 It is apparent that the provision of sufficient pressure in the cylinder 32 will effect a shearing of the screws 26 holding the upper slips 23 to the expander 20, and move these slips outwardly against the casing C, whereupon the cylinder 32 can move upwardly to shift the body 10 in the same direction, expanding the packing sleeve 19 against the casing, and then the lower slips 14 against the casing, as described above. The necessary pressure for performing the desired operational sequence in setting the well packer is supplied by a compressed gas 50 contained within a suitable high pressure bottle or container 51 disposed in the cylinder 32 above the piston 36. The compressed gas may be of any suitable type, such as air, nitrogen, carbon dioxide and the like. It is preferred that the gas be non-combustible for reasons of safety.

70 The gas 50, which may be under high pressure of the order of 5,000 to 10,000 p. s. i., for example, is disposed in the elongate container 51, which may rest on a suitable cylinder shoulder or projecting pins 32a immediately above the piston 36, and which preferably is smaller in diameter than the inside diameter of the cylinder, in order to 75 provide a cylinder space 52a through which the

gas may exert its downward force upon the piston 36, inasmuch as it is preferred to release the compressed gas through the upper end of the container. The lower end of the container may be closed by a suitable plug 52. Its upper end may be closed by a valve device 53, including a valve body 54 threaded into the upper end of the container. This valve body has an inner seat 55 adapted to be engaged by a valve head 56 when the latter moves upwardly with respect to the valve body. A valve stem 57 extends upwardly through the body 54, and may be threaded into an enlarged valve stem portion 58, which projects loosely through a guide and stop nut 59 threaded into the upper end of the valve body. The valve head is urged to closed position by a compressed helical spring 60 whose lower end engages a shoulder 61 in the valve body, and whose upper end bears upon a flange 62 integral with the upper valve stem portion 58, in order to urge the valve head 56 upwardly into engagement with its seat 55.

The lower valve stem portion 57 is substantially smaller in diameter than the passage 63 through the valve body above the valve seat. The enlarged valve stem 58 and flange 62 are also smaller in diameter than the portion of the body bore containing the valve closing spring 60. Similarly, the upper end of the valve stem, which projects through the guide nut 59, is smaller in diameter than the passage through the nut. This relationship of parts is provided to allow the compressed gas to escape through the body portion to the exterior of the container 51 when the valve head 56 is moved downwardly to open position. It is apparent that the compressed gas can then escape around the head 56, the valve stems 57, 58, and the flange 62, in view of the annular clearance spaces allowed.

In order to facilitate filling of the container with the compressed gas, a filling and protective cap 64 may be threaded on the valve body 54 when the container is not disposed within the cylinder 32. This filler cap 64 has a threaded bore 64a for the reception of a suitable pipe or conduit (not shown), that may be connected to a suitable air or gas compressor, or other source of gas pressure. The gas under pressure will automatically unseat the valve head 56 and pass into the container until the container pressure has been brought to the desired value. The release or disconnection of the gas under pressure connected to the cap 64 will allow the valve head 56 to automatically engage its seat 55 and prevent escape of the gaseous contents 50 of the container. The filler cap 64 may then be unthreaded from the body 54 and the container 51 inserted in the cylinder 32, with the projecting rod portion 58a of the valve stem 58 uppermost.

The gas may be released from the container by pressing the valve stem 58 downwardly against the force of its spring 60. The amount of the downward force need not be very great, despite the presence of a high pressure in the container 51, since the effective area of the valve head 56 upon which the high pressure gas in the container acts is relatively small.

The rod 58, 57 is movable downwardly by a valve opening member 65 slidably mounted within an enlarged central bore 66 of a gun barrel portion 67 of the upper cylinder head 34. The valve opening member 65 has longitudinal grooves 68 in which leaf spring holding pawls 69 are mounted. These pawls are secured to the member by screws 70, or the like, and extend in an upward direction

for engagement with ratchet teeth 71 formed in the wall of the gun barrel bore 66. The upper ends of the leaf springs 69 tend to move outwardly inherently into engagement with the ratchet teeth 71, in order to prevent upward movement of the valve opening member 65, but permitting downward movement of the latter. Thus, the valve opening member 65 is disposed initially in an upward position within the gun barrel 67, and then moved downwardly will engage the valve stem 58 to shift the valve 56 downwardly to open position. The latter is held in such open position, since the leaf spring holding pawls 69 engage the ratchet teeth 71 and prevent return or upward movement of the valve opening member 65 and valve stem 58, 57.

The valve opening member 65 may be shifted downwardly by a bullet 72 disposed in the gun barrel 67. The bullet cartridge 73 is clamped in position by a cap 74 threaded into the upper end of the cylinder head 34 and engaging the cartridge. The cap has a central tapered bore 75, through which the lower tapered end 76 of a firing pin 77 may be projected into engagement with the cartridge 73 to shoot the bullet 72, the latter striking the valve opening member 65 and driving it downwardly within the gun barrel 67, to open the container valve 53.

The firing pin 77 is slidably mounted in the bore 78 of a gun body 79 threaded into the upper end of the upper cylinder head 34. Leakage in a downward direction along the firing pin is prevented by one or more suitable side seals 80 in the latter which engage the wall of the gun body. The shaft of the pin 77 extends upwardly and merges into an enlarged head portion 81 having a downward and inwardly tapering surface 82 engageable by correspondingly tapered surfaces on the foot portions 83 of a plurality of latch levers 84 disposed in longitudinal slots 85 in the gun body, and mounted on fulcrum pins 86 secured to the latter.

A compressed helical spring 87 engages the firing pin head 81 and also a coupling pin 88 threaded into the gun body 79, tending to shift the firing pin 77 downwardly into contact with the cartridge 73, in order to fire the bullet 72. However, such downward shifting tendency of the spring 87 is precluded by the latch levers 84, which are held in an inward position, with their foot portions 83 in engagement with the tapered head 81, by a latch retainer sleeve 89 having a lower inwardly directed flange 90 engaging the heel portions 91 of the latch levers. The outer ends 92 of these heel portions 91 are tapered in a downward and inward direction, engaging a companion tapered surface 93 on the flange 90. Such engagement is maintained by a helical spring 94 bearing against the upper end of the gun body 79 and against the latch retainer sleeve 89, urging the latter in an upward direction. However, the retainer sleeve 89 is precluded from moving upwardly beyond a position of alignment of its flange 90 with the latch heels 91, since the tapered surface engagement 92, 93 between such members precludes this movement. Such engagement also prevents the tapered firing pin head 81 and the firing pin 77 itself from being moved downwardly by the compressed spring 87, inasmuch as the latch levers 84 cannot be swung outwardly about their fulcrum pins 86. It is only when the latch retainer sleeve 89 is shifted downwardly along the gun body 79, to remove the sleeve flange 90 from a position of alignment with the heels 91 that the spring 87 is effective to shift the firing

pin 77 downwardly, by causing its tapered head 81 to force the latch levers 84 outwardly, this outward movement being permitted by the enlarged bore 95 provided in the retainer sleeve 89 above its flange 90.

The upper end of the coupling pin 88 is threaded into a rope socket 96 that receives the lower end of the wire line D. The wire line is secured to the socket in any suitable manner, such as by unstranding the lower end of the wire line and connecting it to the socket through use of Babbitt metal (not shown).

The latch retainer sleeve 89 has an upward extension 97 disposed along the wire line socket 96, and terminating at a point above the latter. When it is desired to release the gas 50 from the container 51, a go-devil E may be dropped down the wire line D, striking the upper end of the retainer extension 97 and driving the retainer sleeve 89 downwardly against the force of its compressed spring 94, to remove the flange 90 from alignment with the latch lever heels 91. This removal of restraint allows the spring 87 to expand, shifting the firing pin 77 downwardly to project its tapered end 78 through the cap 14, causing it to strike the cartridge 73. The latter is thereby fired, the bullet 72 striking the valve opening member 65, forcing it downwardly within the gun barrel 67 and into engagement with the valve stem 58, the latter being shifted downwardly to disengage the valve head 56 from its companion seat 55. The compressed gas 50 may now escape from the container, and will continue to escape, since the holding pawls 69 prevent return movement of the valve head 56, valve stem 57, 58 and the valve opening member 65.

The parts are assembled in the relative positions illustrated in Figs. 1, 2a and 2b, with the container 51 holding gas 50 at a comparatively high pressure. The cylinder space around and above the container is preferably filled with a liquid, such as water, so as to reduce the final volume within the cylinder that must be filled by the compressed gas, as the piston 36 moves downwardly within the cylinder 32, thereby insuring a maximum final pressure within the cylinder.

The apparatus is lowered through the well casing to a point at which it is desired to set the well packer. The go-devil E is dropped down the wire line D, striking the upper end of the retainer sleeve 89, and forcing it downwardly to latch releasing position. The compressed spring 87 can then shift the firing pin 77 downwardly, since its tapered head 81 urges the latches 84 outwardly, causing the pin 77 to strike the cartridge 73 and fire the bullet 72. The bullet strikes the valve opening member 65, driving it downwardly and shifting the valve 53 to open position, the holding pawls 69 holding the valve in such open position.

Inasmuch as the area through the valve body 54 through which the compressed gas 50 can escape is relatively small, the gas under pressure will leave the container in a comparatively slow and gradual manner, creating a gradually increasing pressure in the cylinder 32 which urges the piston 36 downwardly therewithin. Such downward movement first releases the upper slips 23 and shifts them outwardly into engagement with the well casing, whereupon the cylinder 32 moves upwardly, as additional gas escapes from the container 51 to increase the pressure within the cylinder 32. This upward movement moves the body 10 upwardly to expand the packing sleeve 19 against the casing C, and then shift the lower slips 14 into engagement with the casing. As the

gas under pressure continues to escape from the container, the slips 14, 23 and packing 19 are urged more firmly against the well casing C, until the shear strength of the connector pin 43 is exceeded, disrupting the latter and disconnecting the setting tool A from the well packer B. The setting tool may now be removed from the well casing by elevating the wire line D.

From the foregoing description and the drawings, it is apparent that an apparatus has been provided, in which the gaseous force is provided in a container 51 that is readily insertable within the setting tool, preferably with its releasing valve 53 uppermost. The container, with gas under pressure therewithin, may be stored until the apparatus is to be used, whereupon it need merely be dropped into the cylinder 32 with its valve uppermost. The valve 53, being at the upper portion of the cylinder, is readily opened by devices disposed thereabove, but the fluid force available within the cylinder is still effective for operation upon the apparatus disposed below the gas container, in view of the clearance space 52a around the latter. The valve 53 is opened against the gas pressure in the container 51 without the exertion of great force, in view of the relatively small effective cross-sectional area of the valve head 56 and the small area of the passage 63 through the valve body. The latter area only allows the gas to escape in a comparatively gradual manner, so that definite time intervals elapse (which may be of the order of several seconds each) between the operational sequences necessary to set the upper slips 23, compress the packing sleeve 19, set the lower slips 14, and release the setting tool A from the well packer B. Once the valve 53 is opened, it is held in open position.

After the setting tool A has been retrieved at the top of the well bore, the cylinder 32 can be dismantled, the spent container 51 readily removed, and a charged container inserted in its place for use in performing another subsurface operation in the well bore.

The inventor claims:

1. In well apparatus: a well device adapted to be operated in a well bore; fluid actuated means connected to said device for operating the same, comprising a closed cylinder and a piston slideable in said cylinder, a normally closed container in said cylinder above said piston and containing a compressed gas, normally closed outlet means for enabling said compressed gas to be released through the upper end of said container, there being a clearance space between said container and cylinder through which said released gas can pass for action upon said piston, and means above said container for opening said normally closed outlet means.

2. In well apparatus: a well device adapted to be operated in a well bore; fluid actuated means connected to said device for operating the same, comprising a closed cylinder and a piston slideable in said cylinder, a normally closed container in said cylinder above said piston and containing a compressed gas, said container having an outlet passage in its upper portion of small area to restrict the escape of gas from said container into said cylinder when said passage is open, means normally closing said passage, there being a clearance space between said container and cylinder through which said released gas can pass downwardly for action upon said piston, and means above said container for shifting said passage closing means to open position.

3. In well apparatus: a well device adapted to

be operated in a well bore; fluid actuated means connected to said device for operating the same, comprising a closed cylinder and a piston slideable in said cylinder, a normally closed container in said cylinder above said piston and containing a compressed gas, valve means in the upper end of said container for confining said gas therein, said valve means including a downwardly opening check valve member operable to release gas from said container, there being a clearance space between said container and the wall of said cylinder through which said released gas can pass downwardly for action upon said piston, and valve opening means above said container engageable with said check valve member to shift said member downwardly to open position and to hold said member in such open position.

4. In well apparatus: a well device adapted to be operated in a well bore; fluid actuated means connected to said device for operating the same, comprising a closed cylinder and a piston slideable in said cylinder, a normally closed container in said cylinder above said piston and containing a compressed gas, valve means in the upper end of said container for confining said gas therein, said valve means including a downwardly opening check valve member operable to release gas from said container, there being a clearance space between said container and the wall of said cylinder through which said released gas can pass downwardly for action upon said piston, valve opening means above said container engageable with said check valve member to shift said member downwardly to open position and to hold said member in such open position, and explosive instrumentalities for driving said valve opening means downwardly.

5. In well apparatus: a well device adapted to be operated in a well bore; fluid actuated means connected to said device for operating the same, comprising a closed cylinder and a piston slideable in said cylinder, a normally closed container in said cylinder above said piston and containing a compressed gas, valve means in the upper end of said container for confining said gas therein, said valve means including a downwardly opening check valve member operable to release gas from said container, there being a clearance space between said container and the wall of said cylinder through which said released gas can pass downwardly for action upon said piston, and valve opening means above said container engageable with said check valve member to shift said member downwardly to open position, and coengaging pawl and ratchet means on said valve opening means and cylinder for preventing upward movement of said valve opening means from its downward position.

6. In well apparatus: a well device adapted to be operated in a well bore; fluid actuated means connected to said device for operating the same, comprising a closed cylinder and a piston slideable in said cylinder, a normally closed container in said cylinder above said piston and containing a compressed gas, normally closed outlet means for enabling said compressed gas to be released through the upper end of said container, there being a clearance space between said container and cylinder through which said released gas can pass for action upon said piston, means above said container for opening said normally closed means, and explosive instru-

mentalities for driving said opening means downwardly.

7. In well apparatus: a well device adapted to be operated in a well bore; fluid actuated means connected to said device for operating the same, comprising a closed cylinder and a piston slideable in said cylinder, a normally closed container in said cylinder above said piston and containing a compressed gas, normally closed outlet means for enabling said compressed gas to be released through the upper end of said container, there being a clearance space between said container and cylinder through which said released gas can pass for action upon said piston, means above said container for opening said normally closed outlet means, said opening means including a rod, means urging said rod longitudinally, a latch engaging said rod to prevent its longitudinal movement, means engaging said latch to prevent its release from said rod, and means for shifting said latch engaging means to a position allowing release of said latch from said rod.

8. In well apparatus: a well device adapted to be operated in a well bore; fluid actuated means connected to said device for operating the same, comprising a closed cylinder and a piston slideable in said cylinder, a normally closed container in said cylinder above said piston and containing a compressed gas, normally closed outlet means for enabling said compressed gas to be released through the upper end of said container, there being a clearance space between said container and cylinder through which said released gas can pass for action upon said piston, means above said container for opening said normally closed outlet means, said opening means including a rod having a downwardly tapering portion, means urging said rod downwardly, a latch engaging said portion to prevent downward movement of said rod, and means engaging said latch to prevent its lateral shifting by said tapering portion to rod releasing position.

9. In well apparatus: a well device adapted to be operated in a well bore; fluid actuated means connected to said device for operating the same; and means operatively connected to said fluid activated means for instituting operation of said fluid actuated means, comprising a rod, means urging said rod longitudinally to initiate operation of said fluid actuated means, a latch engaging said rod to prevent its longitudinal movement, means engaging said latch to prevent its release from said rod, and means for shifting said latch engaging means to a position allowing release of said latch from said rod.

10. In well apparatus: a well device adapted to be operated in a well bore; fluid actuated means connected to said device for operating the same; and means operatively connected to said fluid activated means for instituting operation of said fluid actuated means, comprising a rod having a downwardly tapering portion, means urging said rod downwardly to initiate operation of said fluid actuated means, a latch engaging said portion to prevent downward movement of said rod, and means engaging said latch to prevent its lateral shifting by said tapering portion to rod releasing position.

11. In well apparatus: a well device adapted to be operated in a well bore; fluid actuated means connected to said device for operating the same; and means operatively connected to said fluid activated means for instituting operation of said fluid actuated means, comprising a rod having

a downwardly tapering portion, means urging said rod downwardly to initiate operation of said fluid actuated means, a latch engaging said portion to prevent downward movement of said rod, and a movable retaining sleeve engaging said latch to prevent its lateral shifting by said tapering portion to rod releasing position.

12. In well apparatus: a well device adapted to be operated in a well bore; fluid actuated means connected to said device for operating the same; and means operatively connected to said fluid actuated means for instituting operation of said fluid actuated means, comprising a rod having a downwardly tapering portion, means urging said rod downwardly to initiate operation of said fluid actuated means, a latch engaging said portion to prevent downward movement of said rod, a movable retaining sleeve engaging said latch to prevent its lateral shifting by said tapering portion to rod releasing position, and means for shifting said sleeve longitudinally out of engagement with said latch.

13. In well apparatus: a well device adapted to be operated in a well bore; fluid actuated means connected to said device for operating the same; and means operatively connected to said fluid actuated means for instituting operation of said fluid actuated means, comprising a rod having a tapered portion, means urging said rod longitudinally to initiate operation of said fluid actuated means, a latch engaging said tapered portion to prevent longitudinal movement of said rod, and a movable retaining sleeve engaging said latch to prevent its lateral shifting by said tapered portion to rod releasing position.

14. In well apparatus: a well device adapted to be operated in a well bore; fluid actuated means connected to said device for operating the same, comprising a cylinder and a piston slidable in said cylinder, a container in said cylinder above said piston and containing a compressed gas, valve means in the upper end of said container for confining said gas therein, said valve means including a downwardly opening check valve member, there being a clearance space between said container and the wall of said cylinder through which said gas can pass downwardly for action upon said piston, valve opening means above said container engageable with said check valve member to shift said member downwardly to open position and to hold said member in such open position, and a bullet in said cylinder capable of being fired downwardly against said valve opening means to shift said valve opening means downwardly.

15. In well apparatus: a well device adapted to be operated in a well bore; fluid actuated means connected to said device for operating the same, comprising a cylinder and a piston slidable in said cylinder, a container in said cylinder above said piston and containing a compressed gas, valve means in the upper end of said container for confining said gas therein, said valve means including a downwardly opening check valve member, there being a clearance space between said container and cylinder through which said gas can pass for action upon said piston, valve opening means above said container engageable with said check valve member to shift said member downwardly to open position, explosive means for shifting said valve opening means downwardly, a rod engageable with said explosive means

for firing the same, means urging said rod downwardly into engagement with said explosive means, a latch engaging said rod to prevent its downward movement into engagement with said explosive means, and shiftable means engaging said latch to prevent its release from said rod.

16. In well apparatus: a well device adapted to be operated in a well bore; fluid actuated means connected to said device for operating the same, comprising a cylinder and a piston slidable in said cylinder, a container in said cylinder above said piston and containing a compressed gas, valve means in the upper end of said container for confining said gas therein, said valve means including a downwardly opening check valve member, there being a clearance space between said container and cylinder through which said gas can pass for action upon said piston, valve opening means above said container engageable with said check valve member to shift said member downwardly to open position, explosive means for shifting said valve opening means downwardly, a rod engageable with said explosive means and having a downwardly tapering portion, means urging said rod downwardly, a latch engaging said portion to prevent downward movement of said rod into engagement with said explosive means, and means engaging said latch to prevent its lateral shifting by said tapering portion to rod releasing position.

17. In well apparatus: a well device adapted to be operated in a well bore; fluid actuated means connected to said device for operating the same; and means for instituting operation of said fluid actuated means, comprising a supporting member connected to said fluid actuated means, a rod slidably mounted on said supporting member, means on said supporting member engaging said rod to urge said rod longitudinally, a latch carried by said supporting member and engaging said rod to prevent its longitudinal movement, means on said supporting member and engaging said latch to prevent release of said latch from said rod, and means for shifting said latch engaging means to a position allowing release of said latch from said rod.

18. In well apparatus: a well device adapted to be operated in a well bore; fluid actuated means connected to said device for operating the same; and means for instituting operation of said fluid actuated means, comprising a supporting member connected to said fluid actuated means, a rod slidably mounted on said supporting member and having a downwardly tapering portion, means on said supporting member engaging said rod to urge said rod downwardly, a latch carried by said supporting member and engaging said tapering portion to prevent downward movement of said rod, and a movable retaining sleeve on said supporting member engaging said latch to prevent its lateral shifting by said tapered portion to rod releasing position.
